P. J. CHRISTMAN, JR

CUT-OFF FOR INTERFOLDING MACHINES

Filed Sept. 29, 1923

UNITED STATES PATENT OFFICE.

PETER J. CHRISTMAN, JR., OF GREEN BAY, WISCONSIN, ASSIGNOR TO PAPER CONVERTING MACHINE COMPANY, OF GREEN BAY, WISCONSIN.

CUT-OFF FOR INTERFOLDING MACHINES.

Application filed September 29, 1923. Serial No. 665,603.

To all whom it may concern:

Be it known that I, PETER J. CHRISTMAN, Jr., a citizen of the United States, and resident of Green Bay, in the county of Brown 5 and State of Wisconsin, have invented certain new and useful Improvements in Cut-Offs for Interfolding Machines; and I do hereby declare that the following is a full, clear, and exact description thereof.

10 This invention relates to improvements in interfolding machines and more particularly to the cutting or perforating mechanism for severing the webs of work material into sheets, prior to the interfolding operation.

15 The present invention is particularly designed as an improvement over the cutting mechanism illustrated and described in connection with my Patent No. 1,440,133 issued December 26, 1922, in which a straight cutting knife carried by a roller co-acts with longitudinal slots arranged in the periphery of a bed roll over which the two webs of paper pass. The result of this mechanism is to provide a straight cut in the webs, 20 which cut, in the operation of the interfolding mechanism, must be accurately engaged by the tucker in order that the juxtaposed edges of the severed sheets will be tucked into the fold of the adjacent sheet, as illustrated and described in that patent. In 25 machines of the type just described, it is clear that any lack of alignment of the juxtaposed edges of the severed sheets will cause considerable trouble in the tucking operation. It is clear that in the tucking operation that buckling of the paper will result if the juxtaposed edges are out of alignment with each other, and consequently serious delay or loss of time will result in the 30 operation of the machine.

40 It is, therefore, an object of the present invention to overcome the foregoing disadvantages by the provision of a cutting mechanism which so severs the web as to cause the juxtaposed edges to intermesh with one another, whereby the tucker blade engages both edges regardless of any slight disalignment of the edges with relation to the tucker.

45 A more specific object is to provide a cutting mechanism in which the webs of paper are firmly gripped prior to and during the cutting operation.

With the above and other objects in view, 55 which will appear as the description pro-

ceeds, the invention resides in the novel construction, combination and arrangement of parts substantially as hereinafter described and more particularly defined by the appended claims, it being understood that such 60 changes in the precise embodiment of the herein disclosed invention may be made as come within the scope of the claims.

In the accompanying drawing is illustrated one complete example of the physical 65 embodiment of the present invention constructed according to the best mode so far devised for the practical application of the principles thereof.

In the drawings Figure 1 is a transverse 70 sectional view through a portion of an interfolding machine illustrating the present invention, the relation of parts being shown diagrammatically.

Figure 2 is an enlarged detail sectional 75 view illustrating a fragment of the cutting and body rolls.

Figure 3 is a fragmentary elevational view of the preferred form cutting knife.

Figure 4 is a similar view of a modification.

Figure 5 is a transverse sectional view taken on the line 5—5 of Figure 3.

Figure 6 is a fragmentary detail illustrating the severed intermeshing ends of 85 the work material.

Referring more particularly to the accompanying drawings in which I have only illustrated a sufficient portion of an interfolding machine to enable a thorough understanding of the present invention, the numeral 1 designates a body roll mounted on the shaft 2 and provided at opposite sides with longitudinal recesses or grooves 3 which grooves are provided with recesses 4 adapted to receive the gripping bars 5 constructed of any suitable material, preferably rubber or the like.

Positioned adjacent the body roll and mounted on the shaft 6 is a cutting roll 7 having tangentially secured on its periphery a perforating blade 8, the cutting edge 9 of which is provided with irregular or convoluted cutting teeth.

In the preferred form of the invention, 105 as illustrated in Figure 3, I provide the blade 8 with a saw tooth cutting edge, but inasmuch as the purpose of the invention is to perforate the work material in such manner as to provide intermeshing tongues at 110

the juxtaposed edges, it is obvious that a plate having a convoluted cutting edge 10, as illustrated in Figure 4, would serve a similar purpose.

5. Passing over the body roll 1 and between the cutter roll 7 are two webs of work material A, which, in the operation of the cutting mechanism, are simultaneously severed, and by means of the offset roller 11, the perforation in the outer web is subsequently offset with relation to that of the inner web in order that the proper interfolding operation may be performed.

10 Inasmuch as the interfolding operation is fully described in my previous patent to which reference is made, I have only illustrated a fragmentary portion of the gripping jaws 12, and the tucker blade 13 which perform the same. As illustrated in Figure 1, the tucker blade 13 is so timed and actuated as to engage the inner web A at the perforation and force the same into the gripping jaws 12 which are subsequently actuated to fold the outer sheet.

15 25. In describing the cutting or perforating operation particular reference is had to Figure 2 wherein the associated parts are shown as having just completed the cut, and in which it will be noted that the plate 8 cooperates with the resilient gripping bar 5 to securely hold the webs during this operation. The plate 8 being tangentially secured to the cutting roll 7 first engages the webs A in cooperation with the gripping bar 5 and as the plate enters the groove 3 during the cutting operation, the bar 5, because of its resiliency, compensates for this action and at the same time securely holds the perforated ends of the web until the 30 knife is withdrawn from the groove 3.

40 45. The result of the foregoing operation is to provide a convoluted perforation 14 in the work material, as illustrated in Figure 6 in which the tongues 15 formed in the juxtaposed edges of the sheets intermesh with one another.

From the foregoing it will be seen that as the tucker plate 13 is actuated to tuck the separate edges of the sheets into the fold 50 of the adjacent sheet formed by the jaws 12, both edges, because of the intermeshing tongues, will be engaged regardless of any slight disalignment or parting of the sheets, thus facilitating the tucking operation and 55 preventing buckling of the paper otherwise caused by failure to force both edges into the fold.

I claim:

60 1. In an interfolding machine, the combination of a pair of rolls for receiving two

webs between them, a fluted knife carried by one of said rolls for severing said webs into sheets having intermeshing tongues, means carried by the other roll for pressing said webs against said knife to prevent displacement of said webs, and means for advancing one web with reference to the other web and forming alternate folds in said webs with the tongues of one web positioned within the fold of the other web. 65

2. In an interfolding machine the combination of, means for severing the webs of work material into sheets, comprising a fluted knife adapted to cut the work into sheets and to form intermeshing tongues 75 on the juxtaposed edges of said sheets, and means for engaging said intermeshing tongues to tuck said sheets into the fold of the adjacent sheet.

3. In an interfolding machine the combination of, a body roll over which the work material passes and provided with a longitudinal groove, resilient gripping means mounted within said groove, a cutter roll adjacent to said body roll, a fluted knife 85 mounted on said cutter roll and cooperating with the body roll to sever the webs of work material into sheets and form intermeshing tongues on the juxtaposed edges 90 of said sheets, and means for engaging said intermeshing tongues to tuck said sheets into the fold of the adjacent sheet.

4. In an interfolding machine the combination of, a body roll provided with longitudinal grooves, resilient gripping means 95 mounted within said grooves, a cutter roll positioned adjacent to said body roll, a fluted knife mounted tangentially on said cutter roll and cooperating with the body roll to sever webs of work material into sheets and form intermeshing tongues on the juxtaposed edges of said sheets, and means for engaging said intermeshing tongues to tuck the edges of said sheets 100 into the fold of the adjacent sheet. 105

5. In an interfolding machine the combination of, a body roll provided with a longitudinal groove, resilient gripping means mounted within said groove, a cutter roll positioned adjacent to said body roll, a knife mounted tangentially on said cutter roll and cooperating with said resilient gripping means, whereby the webs of work material are gripped prior to and during the severing operation. 110

In testimony that I claim the foregoing I have hereunto set my hand at Green Bay, in the county of Brown and State of Wisconsin.

PETER J. CHRISTMAN, JR.
